Primary Examiner — Selina Sikder(74) *Attorney, Agent, or Firm* — Taft Stettinius & Hollister LLP(57) **CLAIM**

The ornamental design for a device for control of electric power, as shown and described.

DESCRIPTION

FIG. 1 illustrates a right side perspective view of a device for control of electric power of the present invention.

FIG. 2 is a top, right side view of the device shown in FIG. 1.

FIG. 3 is a bottom, right side perspective view of the device shown in FIG. 1.

FIG. 4 is a front elevation view of the device shown in FIG. 1.

FIG. 5 is a right side view of the device shown in FIG. 1. FIG. 6 is a left side view of the device shown in FIG. 1. FIG. 7 is a top plan view of the device shown in FIG. 1. FIG. 8 is a bottom plan view of the device shown in FIG. 1; and,

FIG. 9 is a rear elevation view of the device shown in FIG. 1.
